UNITED STATES PATENT OFFICE.

WALTER H. NELSON, OF DAYTON, OHIO, ASSIGNOR TO OHMER FARE REGISTER COMPANY, OF DAYTON, OHIO, A CORPORATION OF NEW YORK, (INCORPORATED IN 1902.)

OPERATING DEVICE FOR REGISTERING AND INDICATING MECHANISM.

1,093,720.

Specification of Letters Patent.

Patented Apr. 21, 1914.

Application filed November 7, 1912. Serial No. 729,952.

To all whom it may concern:

Be it known that I, WALTER H. NELSON, a citizen of the United States, residing at Dayton, in the county of Montgomery and 5 State of Ohio, have invented certain new and useful Improvements in Operating Devices for Registering and Indicating Mechanism; and I do declare the following to be a full, clear, and exact description of the 10 invention, such as will enable others skilled in the art to which it appertains to make and use the same, reference being had to the accompanying drawings, and to the letters and figures of reference marked thereon, 15 which form a part of this specification.

This invention relates to new and useful improvements in operating devices for registering or indicating machines of that type in which an indicator controls a distant 20 mechanism in such a manner that the operation of said mechanism is dependent upon the operation of said indicator.

Machines of the above character are usually provided with alining devices to insure 25 the accurate operation of the machine. These alining devices have heretofore been placed in the indicator controlled mechanism. It has been found, in practice, that where long rods are used to connect the indicator with the mechanism controlled thereby, that the friction of these alining devices is sufficient to cause the rods to twist so that the mechanism controlled by the indicator does not operate in exact accordance there- 30 with. In other words, under the prevailing practice, these alining devices often aggra- 35 vate the defects they aim to correct.

One object of this invention is to eliminate this twisting action of the rods caused 40 by the friction of the alining devices, by placing the said alining devices at the indicator instead of in the mechanism controlled thereby.

Another object of this invention is to pro- 45 vide a new and improved operating mechanism for the indicator.

Referring to the accompanying drawings, Figure 1 is a top plan view of my improved operating device, the same being a section 50 on the lines *a—a* of Fig. 6 and *b—b* of Fig. 2; Fig. 2 is a side elevation of the same; Fig. 3 is a section on the line *c—c* of Fig. 2; Fig. 4 is an elevation of an actuator for a register- 55 ing machine; Fig. 5 is a section on the line *d—d* of Fig. 1; and Fig. 6 is a longitu-

dinal sectional view through a car equipped with my invention.

Referring more particularly to the drawings, A represents a portion of a car provided with a registering machine 1 of the type illustrated in the patents to Ohmer *et al.*, 715,129 of Dec. 2, 1902, and 718,867 of Jan. 20, 1903. The said machine is provided with a rear casing 2 which contains the actuator 3 which is common to all the counters 60 of said machine. The said actuator 3 is mounted on a carriage 4 movable along a horizontal guide or track 5. When moved to a proper position relative to a selected counter, the said actuator may be elevated by a 65 gate or lift 6 which is raised by either of the levers 7 in a well known manner. The carriage 4 is moved horizontally to select a counter to be operated by the following means: A sprocket chain 8 is attached to 70 said carriage and surrounds a pulley 9 and a sprocket wheel 10. The wheel 10 is on a shaft 11 which may be termed a setting shaft. When said shaft 11 is rotated, the carriage 4 will be moved in accordance with 75 the direction in which said shaft is turned. The said shaft extends throughout the length of the car and is journaled in bearings 12^a at suitable points. On the end thereof, opposite that upon which the 80 sprocket wheel 10 is placed, is a bevel gear 12 in mesh with a similar gear B on the upper end of a shaft 14 journaled in a standard 85 15. The standard 15 is mounted on the end of the car on which the machine is placed. 90 The lower end of the shaft 14 is provided with a disk 16 journaled in the standard im- mediately below an opening 17 in said stand- 95 ard. The said disk 16 is provided with openings to receive pins 18 which extend from a removable handle 19. The handle 19 extends out through the opening 17 and is provided with a segmental portion 20 hav- 100 ing indications thereon denoting the different classes of fares. When said handle 19 is moved from one side to the other, the shafts 11 and 14 will be rocked and the carriage 4 will be moved accordingly. The indica- 105 tions on the segment portion 20 co- operate with a pointer 21 on the standard 15. The arrangement is such, that, when one of the indications on the segment portion 20 is opposite the pointer 21, the actuator 3 will be opposite the counter in the machine corresponding to that indication. 110

To hold the various parts in their set position, the standard 15 is provided with a member 23 having a plurality of serrations 27 corresponding in number to the number 5 of indications on the segment portion 20. Adapted to ride in and out of the serrations in the member 23, is a roller 24 mounted on a lever 25 pivoted at 26 to the handle 19. The lever 25 is controlled by a spring 28 and 10 when one of the indications on the segment portion 20 is opposite the pointer 21, the roller 24 will lie in one of the serrations of the member 23, thereby holding the operating mechanism in a set position. The car 15 is also provided with a standard 15 on the end of the car opposite that on which the machine 1 is placed, and the handle 19 is adapted to be inserted in the opening 17 of either standard as both standards are 20 provided with a shaft 14 and a disk 16. When one standard is out of use, the opening 17 therein may be closed by sleeve 29 which slides upon said standards and is maintained thereon by a slot and pin. The segment portion 25 20 of the handle 19 may be provided with a shield 30 which is instrumental in preventing the clothing from coming in contact with the roller 24 and lever 25. To permit said roller 24 to be easily placed in engagement with the member 23, when the handle 19 is connected with the disk 16, the lever 25 is provided with an extension 31 which en-

ables said lever 25 to be rocked on its pivot 26 and the roller 24 moved out of the path of the serrated member 23. Owing to the 35 shaft 11 being of considerable length, it is subject to torsional strains, but the alining device, consisting of the serrated member 23, being mounted adjacent to the handle 19, the friction of the carriage 4 will not be 40 sufficient to twist the said shaft 11. The said handle and the carriage will, therefore, always be in their proper relative positions.

Having described my invention, I claim, 45

In a device of the type specified, a standard having an opening therein, an operating shaft journaled in said standard, a pin-receiving disk fixed to said shaft, a handle secured to said disk and extending through 50 the opening in the standard, said handle having a portion provided with indications thereon, a peripheral serrated member secured to the standard, and a lever pivoted to the handle and coöperating with said serrated member to lock said handle in the positions to which it is moved, substantially as specified.

In testimony whereof I affix my signature, in presence of two witnesses.

WALTER H. NELSON.
